UNITED STATES PATENT OFFICE.

GROVER CLEARANCE SINGER, OF OAKLAND CITY, INDIANA.

PORTABLE COAL TIPPLE.

Application filed January 6, 1925. Serial No. 839.

To all whom it may concern:

Be it known that I, GROVER C. SINGER, a citizen of the United States, residing at Oakland City, in the county of Gibson, 5 State of Indiana, have invented certain new and useful Improvements in Portable Coal Tipples, of which the following is a specification.

This invention relates in general to an improvement in portable coal tipples of the 10 type forming the subject-matter of my co-pending application filed July 22, 1924, Serial No. 727,526.

The object of the present invention is the 15 provision of a novel means for leveling and supporting the wheeled platform of the portable tipple when the same is in use and for enhancing the lateral stability of the wheeled platform when the coal tipple is 20 being moved from place to place.

Other objects and advantages reside in certain novel features of the construction, arrangement and combination of parts which will be hereinafter more fully described and 25 particularly pointed out in the appended claims, reference being had to the accompanying drawings forming a part of this specification, and in which:—

Figure 1 is a fragmentary view in elevation illustrating how the improvement is 30 organized with the coal tipple,

Figure 2 is a view in end elevation looking to the right of the wheeled platform,

Figure 3 is a detail view in section on the 35 line 3—3 of Figure 1, and

Figure 4 is a similar view in section on the line 4—4 of Figure 1.

Referring to the drawings it will be seen that a portable coal tipple is 40 designated generally at T and it is to this portable coal tipple that the improvement constituting the present invention is applied. The coal tipple T includes a wheeled platform 16 which may 45 take the form of an ordinary railroad car and which runs on a track 10. For a fuller explanation of the coal tipple, reference is had to my co-pending application, S. N. 727,526, hereinabove referred to.

50 For the purposes of the present invention it will be sufficient to understand that at the right hand of the wheeled platform 16 considerable weight and a relatively high overturning moment are applied.

55 The present invention which provides an auxiliary support for the right hand end of

the wheeled platform which is adapted to level the same and which enhances the lateral stability of the same, is designated generally at A and consists of a self-laying track or 60 "caterpillar" 17 on each side of the wheeled platform at the right hand end of the same and adjustably connected to the wheeled platform. Each self-laying track 17 includes an endless tread or track proper, 65 designated at 18, which is mounted on rollers 19 carried by a frame 20. A vertically adjustable standard or spud 21 is connected to each end of each frame 20 and the spuds 21 of each frame are adjustably mounted on the 70 sides of the wheeled platform or car 16. The mounting of the spuds or standards 21 may be effected in any approved manner, and for the sake of illustration this mounting is shown as consisting of a number of guides 75 22 for each standard or spud. Each guide 22 is fixed to the side of the wheeled platform with which it is associated and has rollers 23, which engage the standard or spud 21.

80 Means is provided for locking and securing the standards or spuds 21 in any of their vertical adjustments or positions and this means may consist of a locking pin 24 provided on each guide, each locking pin being 85 insertible through an opening 25 provided in the guide and being received in any one of a series of sockets 26 provided in the standards 21.

Of course, the pins 24 may be readily removed to release the standards or spuds.

Means is provided for positively raising and lowering the spuds or standards and for this purpose each spud or standard is 95 formed with a rack 27 which meshes with a pinion 28 carried on a shaft 29 driven by suitable gearing from an electric motor or other source of power. If desired the shaft 29 may carry a worm wheel which meshes with a worm fixed on the armature of an 100 electric motor or on a shaft driven from the armature of an electric motor. As shown to advantage in Fig. 2 the lower end of each standard 21 is bifurcated or formed with a yoke 35 which is pivotally connected, as at 36, 105 with a frame 20 of a self-laying track with which the standard is associated. Since the standards or spuds are independently adjustable and since they are pivotally connected to the frames of the self-laying tracks, the self-laying tracks may be made to assume 110 such position as may be necessary to

level up the end of the wheeled platform or car on which the self-laying tracks are mounted. As shown in Figure 2, the self-laying tracks are designed to engage 5 the ends of the cross ties 10^a of the track 10 just outside of the car. In this way the base of the car or wheeled platform 16 is increased so that the lateral stability of the car is enhanced. In traveling from place to 10 place the self-laying tracks may be raised or they may be positioned to engage the ties and provide for lateral stability. If the self-laying tracks engage the ties to provide for lateral stability during the movement 15 of the tipple, they simply idle over their rollers 19 and do not take part in the propulsion of the wheeled platform since the same may be otherwise propelled or drawn. Of course, it is to be understood that in lieu 20 of the pivot openings in the yoke ends 35 of the standards to receive the pivot shafts 36 of the frames 20, slots may be provided so as to provide pin and slot connections between the standards or spuds 21 and the 25 frames 20.

I claim:

1. In a portable coal tipple, the combination with a wheeled platform having the usual running gear, a pair of self-laying 30 tracks arranged on the opposite sides of the wheeled platform, each self-laying track including a frame, rollers carried thereby, and an endless tread mounted on the rollers, a pair of vertically adjustable standards 35 connected with the frame of each self-laying track, means on the wheeled platform for guiding the standards, releasable means for securing the standards in adjustable posi-

tion, and means for vertically adjusting said standards. 40

2. In a portable coal tipple, the combination with a wheeled platform having the usual running gear, a pair of self-laying tracks arranged on the opposite sides of the wheeled platform, each self-laying track including a frame, rollers carried thereby and an endless tread mounted on the rollers, a pair of vertically adjustable standards connected with the frame of each self-laying track, means on the wheeled platform for 45 guiding the standards, and means for vertically adjusting said standards. 50

3. In a portable coal tipple, the combination with a wheeled platform having the usual running gear, a pair of self-laying 55 tracks arranged on the opposite sides of the wheeled platform, each self-laying track including a frame, rollers carried thereby, and an endless tread mounted on the rollers, and a pair of vertically adjustable standards connected with the frame of each self-laying track. 60

4. In a portable coal tipple, in combination with a wheeled platform having the usual running gear, a pair of self-laying tracks associated with the wheeled platform, one self-laying track being on each side of the wheeled platform, means for adjustably connecting the self-laying tracks to the platform, said means including a pair 70 of standards connected with each self-laying track, guides for said standards carried by the wheeled platform, and means for raising and lowering the standards. 70

GROVER CLEARANCE SINGER.
